UNITED STATES PATENT OFFICE.

PAUL B. KLUGH, OF CHICAGO, ILLINOIS, ASSIGNOR TO THE CABLE COMPANY, OF CHICAGO, ILLINOIS, A CORPORATION OF ILLINOIS.

MUSIC-SHEET-CONTROLLING DEVICE.

1,240,160.

Specification of Letters Patent. Patented Sept. 11, 1917.

Application filed November 22, 1911. Serial No. 661,846.

To all whom it may concern:

Be it known that I, PAUL B. KLUGH, a citizen of the United States, residing at Chicago, in the county of Cook and State of Illinois, have invented a certain new and useful Improvement in Music-Sheet-Controlling Devices, of which the following is a full, clear, concise, and exact description, reference being had to the accompanying drawings, forming a part of this specification.

My invention relates to instruments employing a traveling controlling sheet in connection with a tracker or equivalent means for transmitting impulses from the sheet and has as its particular object the provision of means for automatically correcting any deviation of the sheet from its normal path. A further object of my invention resides in the particular arrangement and combination of parts hereinafter described.

Referring to the accompanying drawings, Figures 1 and 1^a are complementary views showing my invention as applied to an automatic player mechanism for a musical instrument;

Fig. 2 is a diagrammatic view showing the electric circuits employed;

Fig. 3 is a detail view taken on line 3—3 of Fig. 1, and illustrating one of the sets of electromagnets;

Fig. 4 is a perspective view showing that part of my invention which co-operates directly with the controlling sheet.

Figs. 5 and 6 refer to a modified form of my invention.

Throughout the various views the same elements are referred to by the same reference numerals.

Referring more particularly to the drawings, 1 is the usual take-up roll, and 2 the music roll of an automatic player mechanism for a musical instrument. These rolls are driven by any preferred form of pneumatic motor such as 3, through intermediate gearing 3' such as is well known in the art. The roll 1 is carried on shaft 4 while roll 2 is supported in the usual manner by shaft 5 and socket 5', which extend through openings in the tracker box 6. Outside of each end of the box 6 is a part of the movable frame 7 in which the shafts 4 and 5 are rotatably mounted. Rods 8—8 pass through from one part of the frame 7 to the other, connecting the two parts rigidly together.

Carried on the right hand part of the frame 7 is the gear mechanism 3' for driving the rolls. At the left hand end of one of rods 8 is carried a bracket 9 which supports the left end of the music roll socket 5'. The movable frame 7 is attached to a pair of pneumatics 10—10 by means of a connecting link 11. The pneumatics 10—10 are provided with two movable plates 12 mounted on a central fixed plate 13, the movable plates 12 being connected by a link 14. The fixed plate 13 is braced to the box 6 by a piece 15. It will now be apparent that if the movable plates 12—12 are operated to the right that the frame 7 will be correspondingly actuated and the music rolls pushed farther to the right by means of the collars 16 carried on the ends of the shaft, whereas if the movable plates 12—12 are shifted to the left the motion of the plates will be transmitted in the same manner, thus moving the rolls 1 and 2 to the left.

The mechanism by which the pneumatics 10 are thus controlled will now be described. To the right of the motor 3 is shown a pneumatic 24. When the vacuum is thrown on the apparatus for playing, the pneumatic 24 is collapsed whereby the end of the arm 25 is caused to come into contact with the spring switch 26, thus forcing it against the contact 27 closing an electric circuit.

At the same time that the arm 25 thus closes the circuit through contacts 26 and 27 it also operates a rod 28 to throw in the clutch which controls the movement of the take-up roll.

Referring more particularly to Figs. 2 and 3, we see that when the circuit is closed at points 26 and 27 the circuit of the battery 29 may pass through the wires 30 and 31 through one or the other of the electromagnets 32, 33 to the contact point 34 or 35. Pivotally mounted so as to swing between the contacts 34 and 35 is a switch arm 36. Whenever arm 36 is in contact with one of its co-operating contact points the battery circuit is then closed through the wire 37. Now it will be understood that the arm 36 is controlled by the position of the music sheet and whenever arm 36 makes contact with one of the points 34, 35 the corresponding magnet 32, 33 will be actuated to attract its co-operating armature 38, 39. Now these armatures act as valves covering the

- inlets to tubes 40 and 41 which lead into the interior of the pneumatic 10. When one of the armatures is lifted from its seat atmospheric air is allowed to enter the corresponding pneumatic 10, thus inflating the pneumatic and operating the rod 11 to change the position of the frame 7 and consequently the position of the music rolls in the manner previously described.
- 10 It will be noted by reference to Figs. 1 and 3 that the magnets 32, 33 are mounted upon the movable plates 12, although in the diagrammatic view in Fig. 2 it would appear that they were separately mounted.
- 15 The manner in which the arm 36 co-operates with the music sheet is best illustrated in Fig. 4 where it will be seen that the arm 36 is one end of a rod 42 which is journaled on a pivoted bracket 43. At the end of the 20 rod 42 opposite from the arm 36 is an arm 44 which contacts with the edge of the music sheet by means of a flattened face as shown.
- In setting up my device it is adjusted so that the apertures in the music sheet register with the corresponding apertures in the tracker board as required for perfect 25 operation. The arm 44 is then adjusted for light contact with the edge of the sheet while at the same time the arm 36 stands 30 midway between the points 34 and 35. The contact between the sheet and the arm 44 can be adjusted as desired by swinging bracket 43 around its pivot point such as 49 by means of some convenient device as 35 for instance the thumb piece 48. Now if the music sheet tends to shift to the right or to the left the arm 36 will make contact with the corresponding point so as to close the circuit of one of the electromagnets 32,
- 40 33 and return the music sheet to its normal position in the manner previously described. It will be seen that the arm 44 is positively moved in one direction by the action of the music sheet, while it is caused to move in 45 the opposite direction to follow the sheet by the weight of the horizontal portion 36.
- It will be seen also by reference to Figs. 1, 1^a and 2, that the branch circuits in which the electromagnets 32, 33 are placed also contain 50 electric lamps 45—45. When the circuits of one of the electro-magnets is closed its corresponding lamp will be lighted, thus giving an indication of the relative position of the perforated sheet 46 with respect to the tracker board 47. Thus the operator is 55 notified whether the sheet tends to run in its correct position or not, and if it tends to run to one side of its proper position the bracket 43 may be adjusted so as to change the relative 60 position of the sheet at which the shifting mechanism is brought into play.
- Referring more particularly to Figs. 5 and 6, Fig. 5 is a front elevation of the modified form of my invention while Fig. 65 6 is a cross sectional view taken on line 6—6

of Fig. 5. In the form of my device shown in Figs. 5 and 6, the electrical features are the same as in the form first described, but the mechanical arrangement is somewhat different. As shown in Fig. 5, rods 8—8 are 70 extended to the left so that the brackets 107—107 support the central board 13 of the pneumatics 10—10, so that the pneumatics move with the shiftable rods 8. Moreover, the brackets at each end of the 75 movable frame are extended up to form bearings 100 for a rod or shaft 101. The rod 101 is bent at one end to form a lever arm which engages with a slotted member 102 which is shown in both Figs. 5 and 6, 80 being dotted in Fig. 6. Carried on the end of rod 101 opposite the pneumatics 10 is a lever arm 103 which carries a cam 104. If now the pneumatics 10 are actuated, the rod 101 is rotated to move the inclined inner face 85 of the cam 104 over the end of the music roll shaft 5, thus moving the music roll longitudinally with respect to the rods 8. The rods 8 are made adjustable with respect to the box 6 by means of a nut 105, which is 90 placed in a recess in the lower member of the box and engages with a screw threaded portion 106 on the lower one of the rods 8. This arrangement of a nut working on a threaded portion of one of the rods 8 may 95 obviously be employed in Figs. 1 and 1^a if desired. By this means the entire gearing for the music and take-up rolls, as well as the shifting pneumatics is set so that the perforations in the music sheet register with 100 the openings in the tracker board and any lack of adjustment due to warping of the music sheet is taken care of by shifting the music roll relatively to the rods 8—8.

In Figs. 1 and 1^a the pivoted bracket 43 is 105 suspended from the tracker box 6, unless equipped with adjusting means such as nut 105, but in the form shown in Fig. 5 this bracket with its accompanying contacts, and swinging contact member is necessarily 110 mounted on a part of the shiftable frame, preferably the central rod 8, so that the bracket may move with the frame when shifted as by the nut 105.

It will be understood by those skilled in 115 the art that while the arrangement shown and described is the preferred form of my invention, that my invention may be applied in various ways. For instance it will be seen that while I have shown two pneumatics 120 for shifting the position of the music rolls that one only might be employed and a guide provided on one edge of the sheet so that it would be prevented from wandering from its correct position upon the side of the 125 guide. Furthermore while I have shown and described a pneumatic as being the immediate means for shifting the position of the music rolls it is apparent that the pneumatics are not essential but that the move- 130

ment might be furnished by solenoids directly instead of by electromagnets controlling the operation of pneumatics. Moreover it will be apparent that only one solenoid 5 might be so used, the function of the other solenoid being taken by a guide as mentioned in connection with the pneumatics.

Accordingly it will be understood that I do not mean to be limited in the application 10 of my invention to the exact arrangement shown but that I contemplate all modifications and rearrangements of the herein described invention which are embraced within the scope of the appended claims.

15 What I claim is:

1. In an automatic sheet controlling device in combination, a pivoted supporting member, a sheet contact member pivoted to said supporting member having an offset portion whose weight tends to turn said contact member about its pivot, means for opposing the turning moment of said contact member, and a pair of electrical contacts mounted on said supporting member, said 20 sheet contact member being thrown into contact with one of said contacts by the weight of said offset portion, and being thrown into contact with the other of said contacts by the action of said means.

2. A sheet shifting device comprising, in combination, a movable roll, pneumatics and connections for moving said roll, electromagnets controlling the operation of said pneumatics, and a circuit closing device for 25 said electromagnets, said device being provided with means whereby it is operated by variation in position of one edge only of the sheet to open or close the circuit for a plurality of electro-magnets.

3. In an automatic sheet controlling device, in combination, a pivoted adjustable member, a contact member pivoted to said adjustable member, said contact member having a projecting face for engaging the 30 edge of a sheet to be controlled and having a horizontal projecting portion whose weight acts to throw said face against the edge of the sheet, and a pair of contacts supported on said adjustable member which 35 operate with said contact member.

4. In an automatic sheet controlling device, in combination, a pivoted contact member having a smooth face for engaging the edge of a sheet to be controlled and having 40 a horizontal projecting portion on the opposite side of the pivot point from said face, and a pair of electric contacts for coöperating with said contact member to control the device.

5. In an automatic sheet controlling device, in combination, a pivoted contact member having a face for contact with the edge of a sheet, said contact member having a 45 projecting portion whose weight acts to throw said face against the edge of the

sheet, and a pair of electric contacts embracing a portion of said contact member, said member being thrown into engagement with one of said contacts by the action of the sheet and being thrown into engagement 70 with the other of said contacts by the weight of said projecting portion.

6. In an automatic sheet controlling device, in combination, a traveling sheet to be controlled, a pivoted support, a contact 75 member pivoted to said support having a face for contacting with the edge of said sheet and having also a portion offset from the pivot point whose weight acts to throw said face against said sheet, and a pair of 80 electric contacts mounted on said support on opposite sides of said contact member, said member being thrown into engagement with one of said contacts by the action of said sheet and into engagement with the other of 85 said contacts by the weight of said offset portion.

7. In an automatic musical instrument, a stationary tracker box, a frame mounted in said box but shiftable relatively thereto, said 90 frame having supported thereon a music roll and a take up roll carrying a traveling sheet, said frame carrying also a pneumatic device, mechanism for shifting the position of said music roll relatively to said shiftable frame 95 operated by said device, and means for controlling said device from the edge of said sheet.

8. In a musical instrument, in combination, a movable frame, a pair of rolls mounted on said frame, an electric contact device 100 mounted on said frame, a pneumatic governed by said device also mounted on said frame, and mechanism operated by said pneumatic for shifting one of said rolls 105 relatively to said frame.

9. The combination of a sheet contacting device, a movable support carrying and movably mounting said sheet contacting device, said support being movable to adjust said 110 sheet contacting device toward and away from said sheet, and electrical contacts located on opposite sides of an extension on said sheet contacting device and arranged so that one or the other of said contacts will 115 be contacted with by a movement of the sheet in one direction or the other.

10. In an automatic musical instrument, in combination, a roll carrying frame, means for shifting said frame relatively to the 120 tracker, and means for shifting one of the rolls relatively to said frame.

11. In an automatic musical instrument, in combination, means for shifting a pair of rolls relatively to the tracker, and means 125 movable with said means for moving one of said rolls.

12. In an automatic musical instrument, in combination, means for shifting one of the rolls with relation to the tracker, and 130

- means for shifting said roll with relation to said first mentioned means.
13. In an automatic musical instrument, in combination, means for shifting a music roll with relation to the tracker, and automatic means for shifting said roll with relation to said first mentioned means.
14. An automatic musical instrument comprising electrical means for controlling the shifting of the music sheet in both directions, and mechanism whereby said means are controlled from one edge only of said sheet.
15. The combination of a tracker board, a pair of rolls, a movable frame in which said rolls are journaled, a pneumatic for shifting said frame relatively to said tracker board, an electromagnet for controlling the pneumatic, and a second pneumatic for controlling the circuit of the magnet.
16. In an automatic sheet controlling device, in combination, an adjustable support movable toward and away from one edge of a traveling sheet to be controlled, a shoe engaging the edge of said sheet, a contact member pivoted to said support operating in one direction by said shoe and having a portion offset from the pivot point whose weight acts to throw said shoe against said sheet, and a pair of electric contacts mounted on said support, said member being thrown into engagement with one of said contacts by the action of said sheet on said shoe and into engagement with the other of said contacts by the weight of said offset portion.
17. A music sheet controlling device having a pivoted support, and a sheet contact member, a pair of electrical contacts, and a switch member, all mounted on said support.
18. A music sheet controlling device comprising, in combination, a support mounted for adjustment relative to the music sheet, a sheet contact member, an electrical switch member, and a pair of electrical contacts, all mounted on said support.
19. In a device of the class described, in combination, an arm contacting with the edge of a music sheet, a switch lever governed by said arm, and means controlled by said lever for adjusting the position of the music sheet.
20. In a device of the class described, in combination, a branched electric circuit, rolls adapted to hold a music sheet, and means for controlling said rolls from one edge only of the music sheet, said means comprising electromagnets in said branched circuit.
21. A music sheet controlling device having a member for contacting with the edge of the music sheet, a lever arm rigid with said member, and a branched electric circuit governed by said arm containing devices for controlling the position of the music sheet.
22. A music sheet controlling device comprising, in combination, an adjustable support, said support being normally stationary during the operation of the device but being adjustable toward and away from the sheet to determine the normal line of travel of the sheet, a pair of electric contacts, a sheet contacting member, and an electric switch arm, said contacts, sheet contacting member and switch arm being all mounted on said support, and said switch arm being operated by the contacting member.
23. In an automatic sheet controlling device, in combination, an adjustable support movable toward and away from the edge of a traveling sheet to be controlled, a shoe engaging the edge of said sheet, a contact member carried by said support and movable relatively thereto, said contact member being operated in one direction by said shoe, means for throwing said contact member in the direction opposite to that in which it is moved by said shoe, and a pair of electric contacts mounted on said support, said contact member being thrown into engagement with one of said contacts by the action of said sheet and said shoe and into engagement with the other of said contacts by said means.
24. In a sheet controlling device, in combination, a pair of electrical contacts, a contact arm pivoted to swing between said contacts, means constantly acting to swing said arm in one direction and into contact with one of said pair of contacts, and means acting at times in opposition to the first mentioned means to swing said arm in the other direction and into contact with the other of said pair of contacts.
25. In a sheet controlling device, in combination with the sheet, a pair of electrical contacts, a contact arm pivoted to swing between said contacts, and means through which the position of said arm between said contacts is varied simultaneously with a variation in the position of the edge of the sheet.
26. In a sheet controlling device, in combination with the sheet, a pair of electrical contacts, a contact arm pivoted to swing between said contacts, and means through which a variation in the position of the edge of the sheet causes a corresponding variation in the position of said arm between said contacts.
27. In a sheet controlling device, in combination, a pair of spaced contacts located at one side of the sheet, a member mounted for movement between said contacts for closing a circuit therewith, and means operable by the sheet to be controlled for moving said member into contact with either of said spaced contacts.
28. In a sheet controlling device, in combination, a pair of spaced contacts located at one side of the sheet, a circuit closing

- switch member intermediate said contacts, said intermediate member and said contacts being relatively movable, and means operable by the edge of the sheet to be controlled 5 for closing the circuit between said intermediate member and either of said contacts.
29. In a sheet controlling device, in combination, a pair of spaced contacts located at one side of the sheet, a circuit closing 10 switch member adapted to form a circuit with either of said contacts, said member and said contacts being relatively movable, and means operable by the edge of the sheet to be controlled for causing said switch 15 member to contact with either of said contacts.
30. In an automatic sheet controlling de-

vice, in combination, a branched electric circuit, a pair of spaced contacts located at one side of the sheet connected one to each 20 branch of the circuit, a conducting switch member coöperating with said contacts for closing the circuit through either of said branches, and means operable by the sheet to be controlled for causing said switch 25 member to contact with either of said contacts.

In witness whereof, I hereunto subscribe my name this fourth day of November, A. D., 1911.

PAUL B. KLUGH.
